RESILIENT PEDAL PAD

William J. Lutey, Seattle, Wash.

Application August 7, 1937, Serial No. 157,905

5 Claims. (Cl. 74—563)

This invention relates to pedal pads in general, and in particular to pedal pads for the foot levers of automotive vehicles that provide a resilient non-slip surface for the feet of the drivers.

The embodiment of the invention herein disclosed comprises a base frame of hard material, that preferably is light and strong and provides a medial window-like opening, upon which a strip of pliable material is wound in figure 8 loops that pass around the side portions of the base, and through the medial openings with a half turn to permit the encircling loops to fit snugly together, and means for adjustably securing the pad thus formed to the pedal.

An object of the invention is to provide an article of the kind described, in which the novel disposition of the pliable material greatly increases its effective resiliency and non-slip features, yet permit its replacement easily and quickly when worn.

Another object is to provide an article of the kind described, that may be readily and adjustably secured to a large number of different size pedals.

A further object is to provide an article of the kind described, that is light in weight yet strong, and that is cheap to manufacture.

Other objects and advantages will be apparent to those skilled in the art from the following detailed description of a preferred form of the invention, which consists of certain parts in co-operative combination, hereinafter described, illustrated in the accompanying drawing, and embraced in the appended claims.

In the drawing:

Figure 1 is a plan view of the pad of my invention secured to a pedal by means of U-bolts and socket nuts.

Fig. 2 is a plan view of a fragmentary portion of the base frame detached from the pedal, showing the beginning of the winding operation.

Fig. 3 is similar to Fig. 2, but shows clearly the half turn twist put in the pliable strip between the second and third bends around the side portions of the frame.

Fig. 4 is a transverse sectional elevation taken on broken line 4—4 of Fig. 1.

Fig. 5 is a fragmentary longitudinal sectional elevation of the pad removed from the pedal, taken on broken line 5—5 of Fig. 1.

Like reference numerals are used to indicate like parts throughout the drawing, wherein the part 6 is a preferred form of base frame that may be made of any hard strong material such

as Bakelite or Masonite, both of which are well known for their characteristic properties. Said base frame preferably provides two window-like openings 6a and 6'a, which divide the frame structure into two wide side portions 6b and 6'b that are joined by end portions 6c and 6'c, and by a mid portion 6d.

The purpose of said mid portion is to reinforce the end portions, thereby providing additional strength without increasing the distance between the ends of the wear surface and corresponding ends of the base frame.

A plurality of counter-sunk holes 7 may be provided in said base frame to receive socket nuts 8 adapted to screw onto the threaded ends 15 of U-bolts 9, which serve to removably secure the pad as a whole to pedal 10, as shown clearly in Fig. 4.

The resilient non-slip wear surface of the pad preferably is formed by interlacing a strip of 20 multiple layer rubberized fabric material 11 with the base frame, and providing means for anchoring the ends of the interlaced strip.

Strips cut from the casings of old automotive vehicle tires have been found to be both inexpensive and ideal for this purpose.

I have solved the troublesome anchoring problem by providing a notch 11n near each end of said strip adapted to engage with an end portion of the base frame.

The start of the interlacing or winding operation is illustrated in Fig. 2 of the drawing. Notch 11n is first engaged with end portion 6c and held there while strip 11 is bent firmly around side portion 6b; next while holding both the loop thus made and the notched end in position, the strip is passed through opening 6a, twisted a half turn about its longitudinal axis in said opening in the direction indicated by the curved arrow line, and bent firmly around side portion 6'b; then while holding this second loop and the notched end in position, the free end of the strip is again passed through opening 6a, twisted a half turn in the direction indicated by the curved arrow line in the opening, and again bent firmly around side portion 6b, as illustrated clearly in Fig. 3; after which the aforesaid passing, twisting and bending operations are continued until the interlacing or winding operation is completed by passing the notched end of strip 11 through opening 6'a to form the last loop; finally the twisted and crossed portions of said strip in opening 6a are forced away from end portion 6'c by a suitable tool, the strip bent firmly around side portion 6'b, and the notch near the end of the strip 55

made to engage said end portion; and lastly the aforesaid tool is removed. In this way I make use of the resiliency of the material to hold the notched ends of strip 11 in engagement with end portions 6c and 6'c, respectively, of the base frame.

5 The thickness, width and length of the resili-
ent strip between notches are made such, that
when the simple winding operation described is
10 completed, both openings 6a and 6b will be snug-
ly filled with the several twisted portions of the
strip, notches 11n will engage with the end por-
tions of the frame, and the several loops about
the side portions thereof will lie closely together,
15 as illustrated in Fig. 1.

Referring to Fig. 4, it will be seen that the
previously described winding operation produces
a succession of figure 8's firmly interlaced with
the base frame. By means of the twist in the
20 resilient strip, the crossing portions of the strip
in the base frame openings nest evenly and close-
ly together, as shown clearly in Fig. 5, which
also illustrates the effective means employed to
anchor the ends of the strip.

25 The half-turn twists in strip 11 cause the edge
corners of successive turns to be raised, as illus-
trated in Figs. 1 and 4. These in combination
with the plurality of turns greatly increase the
30 non-slip features of the pad, even when the driv-
er's shoes are covered with mud or snow.

The small space between the loops of strip 11
and base frame 6 enhance the natural resiliency
of the strip material thereby imparting to the
pedal pad an outstandingly pleasant feeling to
35 the feet of the driver.

When the tread becomes worn, the old strip
may be easily and quickly removed and a new
strip of pliable material wound upon the base
frame as previously described.

40 The counter-sunk holes 7, preferably are so
arranged that they will be at the ends of the
pliable strip winding, or opposite the intervals
between successive turns, as illustrated in Fig. 1.
The pliable material then may be readily forced
45 to one side sufficiently to permit the use of a screw
driver to tighten socket nuts 8.

By providing a plurality of such holes the pad
may be secured to pedals of various sizes and in
several desirable offset positions, one of which
50 is shown in Fig. 4. It will be apparent that when
nuts 8 are tightened upon the U-bolts, the pliable,
non-slip, rubberized material is compressed be-

tween the pedal and base frame of the pad, thus
holding the pad firmly in position.

In view of the foregoing description of a pre-
ferred form of my invention, it will be seen that
my pedal pad is relatively light in weight, and
5 is made of inexpensive materials, hence is cheap
to manufacture.

It will also be apparent to those skilled in the
art, that the essential coating elements may be
constructed and combined in various other equiv-
10 alent forms, and from other materials and for
other uses, without departing from the purpose
and intent of the invention within the scope of
the appended claims.

Having described my invention, what I claim 15
as new and desire to protect by Letters Patent
is:—

1. A pedal pad comprising a base frame pro-
viding a window-like opening, and a strip of
20 pliable material wound upon said frame in a
plurality of figure 8 loops to form a tread sur-
face.

2. A pedal pad comprising a base frame pro-
viding a window-like opening, and a strip of
25 pliable material wound upon said frame and
through said opening in a plurality of figure 8
loops, each with a partial turn in said opening.

3. A pedal pad comprising a base frame pro-
viding side and end portions and a medial open-
30 ing, a strip of pliable material wound in a plu-
rality of figure 8 loops each passing around said
side portions and through said medial opening
with a partial turn to permit said loops to fit
snugly together to form a tread surface, and
means for anchoring the ends of said strip. 35

4. In combination with a pedal, a pad com-
prising a base frame providing a medial opening,
a strip of pliable material wound upon said frame
and through said opening in a plurality of figure
8 loops each with a half turn in said opening, and
40 means for securing said pad to said pedal.

5. In combination with a pedal, a pad com-
prising a base frame providing side and end por-
tions and a medial opening, a strip of pliable
material wound upon said frame in a plurality
45 of figure 8 loops each passing around said side
portions with a half turn in said opening, means
for anchoring an end of said strip to an end por-
tion of said frame, and means for adjustably
securing said pad to said pedal. 50

WILLIAM J. LUTEY.
